UNITED STATES PATENT OFFICE.

PEREGRINE ELLIOTT GLOUCESTER CUMBERLAND, OF ST. KILDA, VICTORIA, AUSTRALIA, ASSIGNOR TO ALEXANDER MARKELL, OF SYDNEY, AUSTRALIA.

MEANS FOR PREVENTING CORROSION OF SURFACE CONDENSERS AND OTHER METAL STRUCTURES.

1,020,480.

Specification of Letters Patent. Patented Mar. 19, 1912.

Application filed April 27, 1911. Serial No. 623,609.

To all whom it may concern:

Be it known that I, PEREGRINE ELLIOTT GLOUCESTER CUMBERLAND, a subject of the King of Great Britain, residing at St. Kilda, State of Victoria, Commonwealth of Australia, have invented certain new and useful Improvements in Means for Preventing Corrosion of Surface Condensers and other Metal Structures, fully described and represented in the following specification and the accompanying drawings, forming a part of the same.

This invention relates to means for preventing corrosion of surfaces of metallic structures or bodies in contact with water or other liquids, and the invention relates more especially to means for preventing corrosion of parts of surface condensers in contact with the injection water. The tubes for the circulation of the injection water and some other parts of such condensers are usually made of brass, bronze or copper, and the partial or complete destruction of such parts as well as of other parts made of other metals through corrosion, and especially electrochemical, or electrolytic, corrosion, has heretofore been a serious obstacle to the successful and economical use of such condensers. This destructive corrosion is especially noticeable in the case of condensers having sea water injection.

Electrolytic corrosion of metallic surfaces occurs whenever an electric current passes from a metallic surface directly to an electrolyte. Such flow of current may result from the production of local currents by galvanic, or voltaic, action between molecules or particles of different metals in a metallic mixture or alloy, or between masses or bodies of different metals conductively connected and also in connection through the electrolyte, and may also be caused by stray currents which reach and tend to escape from a metallic body or structure. Such electrolytic corrosion and also corrosion which results solely from chemical action may be prevented by maintaining between the metallic body or structure and an anode also in contact with the electrolyte, a difference of potential such as to produce an electromotive force tending to cause a flow of current to the metallic body or structure from the electrolyte greater than the electromotive force tending to cause a

flow of current from any part of the metallic body or structure to the electrolyte. Such counter electromotive force acts to prevent the flow of current from any part or particle of the surface of the metallic body or structure into the electrolyte, thus preventing electrolytic corrosion, and the current flowing through the electrolyte from the anode to the metal to be protected causes hydrogen to be formed and to collect against the surface of the metal, which hydrogen protects the surface from chemical corrosion. This method of protecting metal against corrosion has been proposed heretofore and has been successfully employed by me, as described, for example, in my U. S. Letters Patent Nos. 921,641 and 948,968. It has also been proposed by others to protect the parts of surface condensers in accordance with this method, but so far as I am aware no practical means for supplying this method to the protection of surface condensers has been devised prior to my invention.

The present invention aims especially to provide a practical, reliable and efficient apparatus or means for applying this method of protection to surface condensers, features of the invention, however, being capable of application for the protection of other structures, such as other forms of liquid containers; and the invention relates further to means whereby an indication will be given when an anode, through the corrosion which is diverted to it from the parts to be protected, becomes reduced to or near the point where it should be replaced with a new one.

A full understanding of the invention can best be given by a detailed description of a preferred embodiment of the same as applied to a surface condenser, and such a description will now be given in connection with the accompanying drawings, showing such a preferred embodiment of the invention.

In said drawings:—Figure 1 shows in longitudinal section a common form of horizontal surface condenser provided with means embodying the present invention for preventing corrosion of the parts of the condenser in contact with the injection water. Fig. 2 is an enlarged sectional view of one of the anodes and the supporting

and insulating means by which it is attached to the wall of the condenser.

Referring to the drawings, A represents a surface condenser having a cylindrical shell or casing 10 with removable end plates or heads 11, and provided with a steam inlet 12 and an outlet 13 for the water of condensation. Within the casing are arranged the tubes 15 for the passage of the injection water supported at their ends by the usual tube plates 16 and opening to chambers formed between the tube plates and the end plates 11, the space between the tube plate and the end plate at one end of the condenser being divided by the usual baffle plate 17 to form an inlet chamber 18 to which the injection water is supplied through a supply pipe 19 and a discharge chamber 20 from which the water is discharged through an overflow pipe 21. When the condenser is in operation the injection water supplied to the chamber 18 will flow through the lower tubes to the chamber 22 at the opposite end of the condenser and thence through the upper tubes to the discharge chamber 20 and out through the pipe 21.

Referring now to the means shown for carrying out the invention in connection with a condenser of the form shown, a plurality of blocks or bodies 30 of suitable material to serve as positive electrodes or anodes are mounted within the condenser casing. Preferably one such body or anode will be mounted in each of the chambers 18 and 20 of the condenser shown and two such anodes in the opposite end chamber 22. These anodes should be set away from the walls or other parts of the condenser and thoroughly insulated therefrom, and they will be connected with the positive side or pole of a suitable source of electric energy supplying a direct current, the opposite side or negative pole of which is connected with the condenser structure. As shown, the source of electric energy is represented as a generator 35 having its negative pole connected by a wire *a* with the condenser casing and having its positive pole connected by line *b* with the several anodes 30 through branch lines *c* of which one leads to each anode. The source of energy must be of such character and capacity as to maintain a difference of potential between the anodes and the parts of the condenser in contact with the injection water sufficient to cause a flow of current to all parts of the condenser from the injection water under an electromotive force which is greater than the electromotive force tending to cause a flow of current from such part of the condenser to the injection water, and to supply an amount of current to each anode in excess of the aggregate amount of current which would in the absence of the protecting current flow from the part of the structure

which each anode is to protect. In practice, a voltage very much in excess of that actually required may be used without any bad results, and a voltage considerably in excess of that required is preferably employed. A considerable excess amperage is also not objectionable aside from the fact that the rapidity of destruction of the anodes is in proportion to the flow of the counter current. The amount of current required is, however, comparatively small and a safe excess should be used because of the difficulty or impossibility of determining the exact amount of current required except by noting the results obtained. Under ordinary conditions with even a comparatively large condenser of the form shown and with the anodes arranged as shown, I find that a current of one ampere supplied to each anode affords full protection.

To secure the proper supply of current to each of the several anodes, the anodes are connected in circuit through separate branch lines as before stated and in each branch line there is provided a current limiting or determining means shown as a resistance 36 which is adjusted or adapted for supplying the desired amount of current through each anode. With the anodes arranged as shown, a substantially equal amount of current should be supplied to each anode. For providing such a resistance, I preferably employ filament lamps, both as a matter of convenience and because they serve also as visual indicators showing interruption of the circuit to the several anodes occurring from any cause, such as lack of water in the condenser or a break in the metallic circuit. An ampere meter 37 is preferably provided to indicate the direction of flow of the current and the total amount of current flowing through the protecting circuits. The main line of the circuit will also be provided with a controlling switch and safety fuses as indicated.

All parts of the condenser to be protected must of course be conductively connected with the negative side of the source of current. In condensers as ordinarily constructed the various parts are so connected as to provide good metallic contact between its various parts, and the single connection as shown with the source of current will ordinarily be sufficient.

In the use of the apparatus, when the switch is closed to supply current to the anodes and the condenser shell is supplied with water, the anodes will be electro-positive with relation to the parts of the condenser and the counter electromotive force under which the current tends to flow from the injection water or electrolyte to the parts of the condenser in contact therewith will prevent the flow or escape of current from any part or particle of such parts of

the condenser and corrosion of such parts will be prevented. And, furthermore, in addition to preventing corrosion, the flow of the counter current will prevent incrustation of the condenser surfaces or the formation of scale. Thus, not only will complete or partial destruction of the tubes and other parts of the condenser be prevented, but incrustation and consequent impairment of efficiency will also be overcome. The anodes will be more or less rapidly corroded, and when so far gone as to seriously impair their efficiency they will be replaced with new ones.

15 The anodes 30 may be of any suitable material and of any suitable form, but for economy and efficiency are best made of iron, and a convenient and suitable form is that of a flat circular body as shown. They 20 may be supported and insulated in any suitable manner providing for connection with the wires *c* and for the removal of used up anodes and attachment of new ones, but the supporting and insulating means 25 shown is preferred and forms a feature of the invention. This supporting device comprises a metal bolt or bar 40 having one end screwed into a threaded socket 41 in the plate or body forming the anode. This 30 bolt or bar passes through and is insulated from and secured in an opening in the plate forming the head 11 of the condenser. It is of sufficient length to support the anode at a substantial distance from the condenser 35 head or other wall to which it is attached with its outer end projecting outside the wall to receive the nuts 42. A portion of the bolt between the condenser head and the anode carrier and is protected by a sleeve 43 40 of fiber or other suitable strong insulating material. Between the end of the sleeve 43 and the anode is placed a washer 44 of rubber or other insulating material suitable for making a water tight joint, and a similar rubber washer 45 is placed between the 45 sleeve and the condenser head 11. The hole in the condenser head is made somewhat larger than the bolt 40 to receive a ferrule 46 of fiber or other suitable insulating material which is best made of a length to extend inward past the washer 45 and into a socket formed in the end of the sleeve 43 and to extend outward through a washer 47 of fiber or other suitable insulating material which 50 is placed between the condenser head and the inner nut 42. A protecting metal washer 48 is also preferably provided between the inner nut and the washer 47, and this washer 48 best has an opening of sufficient size to receive the end of the ferrule 46. When the parts are thus assembled with the bolt and ferrule in the opening in the condenser head, the tightening of the inner nut 42 will draw the bolt outward, 55 thereby causing the rubber washer 44 to

be clamped tightly between the sleeve 43 and the anode and the washer 45 to be clamped tightly between the sleeve and condenser head, thereby effectually preventing access of water to the bolt. The washer 47 70 will also be clamped tightly against the condenser head and with the ferrule 46 will serve to insulate the bolt and nuts from the condenser head. By having the ferrule of sufficient length to extend through the 75 washers 45 and 47 and into the recessed end of the sleeve 43, possible danger of short circuiting through the medium of any water which might possibly gain entrance is practically eliminated. It will be seen that with 80 the anode supported in this way the supporting device is effectually insulated both from the condenser structure and from the water, and that there is no part of the support between which and any part of the 85 condenser structure there is a path of less resistance for the current than between the anode itself and parts of the condenser structure, and also that the anode is supported without any part thereof in close 90 proximity to any part of the condenser.

It is desirable that means be provided for giving some indication outside of the condenser when an anode has, through corrosion from the current passing from it to the electrolyte, been reduced in size to such a point that a new anode should be provided. To provide such means, the anode support, the bolt 40 in the construction shown, is provided with a small passage or bore 50 extending from its inner end or a point which is normally closed by the anode to a point at its outer end outside the condenser casing. This passage will be sealed at its inner end so long as the anode covers the end 100 of the bolt, but when corrosion of the anode has progressed to such an extent that the end of the bolt is exposed the passage will thereby be opened and water will flow out from the condenser through the passage. 105 The escape of water from the tell-tale passage 50 of any one of the anode supporting bolts will thus show that that particular anode has been corroded to such an extent that a new anode should be placed in position. By varying the depth of the socket 41 in the anode or by otherwise changing the position of the inner end of the passage 50, which is normally sealed by the anode or a part thereof, the indication may be 110 caused to be given for whatever condition of the anode it is considered should call for the renewal of the anode.

It will be seen that one important feature of my invention comprises a source of electricity, to the negative pole of which is connected the metalwork of the apparatus to be protected, while to the positive pole of said source of electricity is connected a plurality of branch lines or wires in parallel with 125

each other, these branch lines being arranged to carry current to the anode surface, the total amount of such anode surface necessary for the protection of the apparatus being sub-divided into portions distributed throughout the interior of the apparatus to be protected. These portions, each of which I will designate generally as an anode device, are insulated from the apparatus to be protected and located in the path of the water, each anode device serving to protect that portion of the apparatus in its vicinity. Furthermore each anode device is connected to its own branch line only, whereby by providing suitable resistance in the branch lines each anode device may have the voltage impressed upon it controlled or determined independently of the voltage impressed upon any other anode device. In the particular embodiment of the invention shown in Fig. 1 of the drawings, each anode device consists of only one anode because in a structure of the size generally indicated in Fig. 1, a single anode at the termination of its respective branch line can be made conveniently of such a size as to perform its necessary function and yet not be too large to be readily supported so as to be mechanically strong and properly insulated from the apparatus without danger of injury to the insulation.

As hereinbefore explained in the specification, the anodes should be set away from the walls or other parts of the condenser or other apparatus to be protected and in the example shown the anodes are supported substantially in the middle of the respective chambers. This is for the purpose of obtaining a substantially uniform distribution of the current from the anode to the various adjacent parts of the apparatus to be protected. If the anode is placed in substantially close contact with either wall so much of the current would return through such wall that it would be difficult to drive enough current to other parts of the apparatus to protect the same.

It will be understood that the invention may be employed in connection with surface condensers of various forms, whether for marine or land use, and that features of the invention, as claimed, may be applied to or used for the protection of, other structures.

It will be understood also that the invention is not to be limited to the exact construction and arrangement of parts as shown, but that it includes changes and modifications thereof within the claims.

What I claim is:

1. In a system for preventing corrosion, the combination, with the apparatus to be protected, of a source of electricity, means for connecting the said apparatus to the negative pole of said source of electricity, a

plurality of branch lines connected to the positive side of the source of electricity, a plurality of anode devices located within the apparatus to be protected and insulated therefrom, each anode device being connected to one branch line only, and means for controlling and determining the voltage impressed on each anode device independently of the voltage on any other anode device. 75

2. The combination with a surface condenser, of means for preventing corrosion of parts thereof in contact with the injection water comprising a plurality of anodes mounted within the condenser casing and insulated therefrom, a source of electrical energy, means electrically connecting the parts of the condenser to be protected with the negative side of the source of electrical energy, a separate branch line connection leading from each anode to the positive side of the source of electrical energy, and a resistance in each of said branch lines for controlling and determining the amount of current supplied through each anode. 80

3. The combination with a surface condenser having water chambers at the ends of the tubes including an inlet chamber and a discharge chamber, of means for preventing corrosion of parts of the condenser in contact with the injection water comprising a plurality of anodes mounted one or more in each of the water chambers and insulated from the condenser, a source of electrical energy, means electrically connecting the parts of the condenser to be protected with the negative side of the source of electrical energy, a separate branch line connection leading from each anode to the positive side of the source of electrical energy, and a resistance in each of said branch lines for controlling and determining the amount of current supplied through each anode. 90

4. The combination with a surface condenser, of means for preventing corrosion of parts thereof in contact with the injection water comprising an anode mounted within the condenser casing, a support for the anode formed of a metal bar extending through an opening in and secured to the condenser casing, means for insulating said metal bar from the shell and from the water, a source of electrical energy, and means electrically connecting the parts of the condenser to be protected with the negative side of the source of electrical energy and the anode support with the positive side of the source of electrical energy. 105

5. The combination with a surface condenser, of means for preventing corrosion of parts thereof in contact with the injection water, comprising a plurality of anodes mounted within the condenser casing and insulated therefrom, a source of electrical energy, means electrically connecting the 110

parts of the condenser to be protected with the negative side of the source of electrical energy, connections from the anodes to the positive side of the source of electrical energy, and indicating means for each anode arranged to indicate the time for renewal of said anode.

6. The combination with a metallic body or structure, of means for preventing corrosion of parts thereof in contact with liquid comprising a plurality of anode devices mounted in position to be in contact with the liquid with which the parts of the structure to be protected are in contact, said anode devices being insulated from said body or structure, a source of electrical energy, means electrically connecting the parts of the body or structure to be protected with the negative side of the source of electrical energy, a separate branch line connection from each of said anode devices to the positive side of the source of electrical energy, and a resistance in each of said branch lines for controlling and determining the amount of current supplied through each anode.

7. The combination with a metallic body or structure, of means for preventing corrosion of parts thereof in contact with a liquid comprising a plurality of anode devices mounted in position to be in contact with the liquid with which the parts of the structure to be protected are in contact, said anode devices being insulated from said body or structure, a source of electrical energy, means electrically connecting the parts of the body or structure to be protected with the negative side of the source of electrical energy, a branch line connection from each of said anode devices to the positive side of the source of electrical energy, and a filament lamp in each of said branch lines to control and determine the amount of current supplied through each anode device and to serve as an indicator to show the condition of each branch circuit.

8. The combination with a liquid containing structure, of means for preventing corrosion of parts of the structure in contact with the liquid, comprising an anode mounted within the structure in position to be in contact with the liquid in the structure and insulated from the structure, a source of electrical energy, means electrically connecting the parts of the structure to be protected with the negative side of the source of electrical energy and the anode with the positive side of the source of electrical energy, and a tell-tale passage extending from a point within the anode to a point outside the structure whereby when the anode has been reduced by corrosion sufficiently to expose the end of the tell-tale passage water will pass out through the passage.

9. The combination with a liquid containing structure, of means for preventing cor-

rosion of parts of structure in contact with the liquid, comprising an anode mounted within the structure in position to be in contact with the liquid, a support for the anode formed of a metal bar extending through an opening in and secured to an outer wall of the structure at a point below the water level, means for insulating said supporting bar from the wall of the structure and from the liquid, a tell-tale passage extending through the supporting bar from a point within the anode to a point outside the structure, a source of electrical energy, and means electrically connecting the parts of the structure to be protected with the negative side of the source of electrical energy and the anode support with the positive side of the source of electrical energy.

10. The combination with a metal body adapted to serve as a positive electrode, of an insulating support therefor having a tell-tale passage extending from the outer end of the support to a point within the anode.

11. The combination, with an electrode, of a bar of conducting material secured to the electrode, a sleeve and a ferrule of insulating material mounted on said bar, a washer between the sleeve and the electrode, a pair of washers surrounding the ferrule, and means for drawing the bar in a direction to pull the electrode toward the sleeve and compress the washers.

12. The combination with the metal body to be used as a positive electrode, of a supporting bar, to one end of which the electrode is secured, an insulating sleeve on the bar, washers at the ends of the sleeve, an insulating ferrule to pass through an opening in a wall or plate to which the supporting bar is secured, said ferrule extending through the washer and into a recess in the end of the sleeve, an insulating washer to engage the outer side of the plate or wall to which the bar is secured, and means for drawing the bar outward against the resistance of the sleeve whereby the insulating washers will be compressed and the bar will be securely positioned.

13. The combination, with the metal body to be used as a positive electrode, of a supporting bar, to one end of which the electrode is secured, an insulating sleeve on the bar, an insulating ferrule to pass through an opening in a wall or plate to which the supporting bar is secured, said ferrule extending into a recess in the end of the sleeve, an insulating washer to engage the outer side of the plate or wall to which the bar is secured, and means for drawing the bar outward against the resistance of the sleeve whereby the sleeve will be clamped in place and the bar will be securely positioned.

14. In a system for preventing corrosion, the combination with the apparatus to be

- protected, of a plurality of anode devices located within said apparatus and insulated therefrom, means for establishing an electro-motive force at each anode device independent of the electro-motive force at any other anode device, and means for connecting said apparatus as a cathode for each anode device. 5 a surface of insulating material to the liquid between the anode and the structure, whereby current to pass through the liquid to the structure will be delivered only at a point remote from all portions of the structure to be protected. 35
15. In a system for preventing corrosion, the combination with a liquid containing structure to be protected, of a plurality of anode devices located within said structure and insulated therefrom, means for supplying electric current to said anode devices, 10 said structure being connected to said means to serve as a cathode for each anode device, and means for determining the amount of electric current supplied through each anode device independently of the amount supplied through any other anode device. 15 40
16. The combination with a liquid containing structure, of means for preventing corrosion of parts of the structure in contact with the liquid, comprising an anode and means for supplying current to the anode and for connecting the structure to act as a cathode, said anode being located within the structure in position to be in contact with the liquid in the structure and 20 carried by an insulating support extending from a part of the structure below the surface level of the liquid and supporting the anode at a substantial distance from said part of the structure and formed to present 25 45
17. The combination, with an electrode, of a supporting bar of conducting material to one end of which the electrode is secured, means for securing the supporting bar in an opening in a wall or plate with the electrode at a substantial distance from the wall or plate, and means for insulating the supporting bar comprising a sleeve of insulating material forming an outer covering of the supporting bar. 50
18. The combination, with an electrode, of a supporting bar of conducting material to one end of which the electrode is secured, means for securing the bar in an opening in a wall or plate with the electrode at a substantial distance from the wall or plate, and insulating means comprising a sleeve of insulating material forming an outer covering of the supporting bar between the electrode and the wall or plate. 55 50

In testimony whereof, I have hereunto set my hand, in the presence of two subscribing witnesses.
